(57) **CLAIM**

The ornamental design for a charger device, as shown and described.

DESCRIPTION

FIG. 1 is a top perspective view of a charger device in accordance with the present design;

FIG. 2 is a top plan view thereof;

FIG. 3 is a bottom plan view thereof;

FIG. 4 is an enlarged front elevation view thereof;

FIG. 5 is an enlarged rear elevation view thereof;

FIG. 6 is a right side elevation view thereof; and,

FIG. 7 is a left side elevation view thereof.

The broken lines showing portions of the charger device in the drawings are included for the purpose of illustrating environmental structure and form no part of the claimed design.
